Des. 230,240
Patented Feb. 5, 1974

230,240

COASTER

Michael S. Kaffel, 515 E. 89th St.,
New York, N.Y. 10009

Filed Nov. 10, 1972, Ser. No. 305,562

Term of patent 14 years

Int. Cl. D7—06

U.S. Cl. D7—45

FIG. 1 is a top plan view of a coaster showing my new design,

FIG. 2 is a side elevational view of the coaster, and FIG. 3 is a sectional view of the coaster through line 3—3 of FIG. 1.

I claim:

The ornamental design for a coaster, substantially as shown.
